Dec. 12/18

Dear all whom it may concern:

Be it Known that I, J. C. Karr, of the County of Williamson,
and State of Tennessee, have invented or produced a certain new and original
Design, for Coffins, and I do hereby declare that the accompanying drawings, represent
the design and configuration of my coffin.

What I claim as new and desire to secure by Letters Patent,
is the form and configuration for a design for Coffin herein shown.
